UNITED STATES PATENT OFFICE.

ALLAN S. BARROWS, OF CHICAGO, ILLINOIS.

METAL DOOR.

Application filed May 8, 1919, Serial No. 295,603. Renewed July 22, 1921. Serial No. 486,808.

To all whom it may concern:

Be it known that I, ALLAN S. BARROWS, a citizen of the United States, residing at Chicago, in the county of Cook and State 5 of Illinois, have invented a certain new and useful Improvement in Metal Doors, of which the following is a full, clear, concise, and exact description, reference being had to the accompanying drawings, forming a 10 part of this specification.

This invention relates to improvements in metal doors.

In railway practice, considerable difficulty has heretofore been encountered in connection with the maintenance of side doors of 15 box cars. Originally, all such doors were made of wood but the same have proven unsatisfactory for the conditions encountered because of the excessive weight of such 20 wood doors and their inflammability, and furthermore because of the distortion, sagging, splintering and mutilation thereof resulting from the manner in which they are opened and closed by the use of crow-bars 25 and other heavy tools commonly employed.

Many attempts have, of course, been made to overcome the difficulties above noted, both by inventors and railroad officials and to substitute therefor an all-metal door or a 30 combination wood and metal door. These attempts, however, have been more or less unsatisfactory due to the fact that they have necessitated excessive weight which not only causes a heavy initial cost but forms an 35 unnecessary dead weight or unproductive load of the car as a whole.

The object of my invention is to provide an all-metal door especially adapted for side doors of box cars although its application 40 is not necessarily limited thereto, and in which I employ a minimum amount of material consistent with the necessary strength and concentrate the material at those parts where the greatest strains are 45 imposed. The invention also contemplates such a metal door as is composed mainly of sheet metal of relatively extreme thinness reinforced at those points particularly subject to indentation, bending or distortion.

50 Another and more specific object of the invention is to provide a metal door of the character indicated, particularly designed for use on railway cars where the doors are supported at the bottom by rollers and 55 in which specific embodiment of my invention, the reinforcing members applied to the

main sheet metal part of the doors either provide an excellent supporting track for the door on which said rollers bear or may be adapted to form the support for the roller journals, the rollers in the latter case extending below the edge of the door and riding upon a track supported directly by the car body.

Another object of my invention is to provide a metal door, particularly adapted for railway box car doors and which is in the nature of an improvement of the invention disclosed in my allowed pending application 70 #185,411, filed August 10, 1917 for improvement in sheet metal car doors, one feature of the improvement being, broadly, to facilitate and cheapen the fabrication of the door, as compared with the structure disclosed in said co-pending application. Broadly stated 75 the cost of fabrication is materially lessened by eliminating certain of the bending operations required on the marginal portions of the door illustrated in said copending application #185,411.

80 The invention furthermore consists in the improvement in the parts and devices and in the novel combinations of the parts and devices herein shown, described and made 85 the subject matter of claims.

In the drawings forming a part of this specification, Figure 1 is a side elevation of a metal door embodying my improvements. Fig. 2 is a vertical, sectional view, taken substantially on the line 2—2 of Fig. 1. 90 Fig. 3 is a horizontal sectional view taken substantially on the line 3—3 of Fig. 1. Figs. 4 and 5 are views corresponding to Fig. 3 but illustrating two other embodiments of the invention. Figs. 6, 7, 8 and 95 9 are horizontal sectional views corresponding to Fig. 3 but illustrating only one edge of the respective doors, the remaining parts being broken away in order to permit the location of the views on the sheet, said Figs. 6 to 9, inclusive, illustrating still other embodiments of the invention. Figs. 10 to 14, 100 inclusive, are vertical sectional views, partly broken away in each instance, corresponding to Fig. 2 of the drawing and illustrating 105 still other embodiments of the invention, as hereinafter explained.

110 Referring first to the construction illustrated in Figs. 1, 2 and 3, the door is illustrated as of the usual rectangular form and comprises three panels A, B and C, upper reinforcing Z-bar D, lower reinforcing

Z-bar E, edge reinforcing Z-bars F and G and horizontal reinforcing angle irons H—H where the panels are united.

Each of the panels A, B and C is made of relatively thin sheet metal and in order to reduce this thickness to the greatest extent possible consistent with the necessary strength, the panels are provided with suitable strengthening corrugations which in the 10 instance shown, extend horizontally as indicated at 20—20. In addition, the panels A are provided with vertical corrugations adjacent their respective end edges, as indicated at 21—21, the edge corrugations 21 of all the panels being made in alinement as clearly indicated in the drawing. Said edge corrugations 21 may be merged into the uppermost and lowermost horizontal corrugations as indicated at 22—22 at the corners 20 of the door. It will be observed that all of the corrugations preferably extend outwardly, that is, from the inner plane of the door, to thereby facilitate sliding the door back and forth in proximity to the side wall 25 of the car. The panels A, B and C are preferably overlapped along their meeting horizontal edges and riveted as indicated at 23, these junction lines being reinforced by the angle irons H—H. As is well known, the 30 greatest outward thrust or pressure on doors of box cars is at the bottom of the door, the outward thrust gradually lessening as the top of the door is reached and, in view of this condition and in order to still further 35 lessen the weight of the sheet metal, I may make the panels A, B and C of varying thicknesses, the upper panel A being the thinnest, the intermediate panel B slightly heavier and the lower panel C still heavier, 40 the variations, however, preferably not being in excess of 1/64th" for the different panels, and although this difference appears slight, the resultant saving in weight and initial cost is very appreciable when the two 45 doors of the car are considered.

As is well known, the vertical edges of the door are subjected to severe service, particularly as the operators use crow-bars or any other tool to force the doors from closed to 50 open position and frequently in the opposite direction. When the load is against the doors, it is, of course, difficult to shift them and the crow-bars are then brought into play. In order to minimize the effects of 55 this practice, the vertical edge Z-bars F and G are employed, the same being applied as most clearly shown in Figs. 1 and 3. In practice, the sheet metal panels A, B and C will be provided with a marginal flat portion 60 as indicated at 24 on the right hand edge and with a corresponding flat portion 25 on the left hand edge, the sheet at the left hand edge, however, being extended and bent at right angles to the door as indicated at 25 to form a seal. The Z-bars F and

G are applied with one flange 26 riveted or spot-welded to the marginal portions 24—24 of the sheets, the other flanges of the Z-bars being extended over the vertical edge corrugations 21 and riveted or spot-welded thereto so as to form an extremely rigid brace for the edges. The effect of riveting the flat edges 24 of the sheets and flanges 26 of the Z-bars produces a multiply-edge which in itself is adapted to effectively resist indentation and the bridging effect or trussing of the edge corrugations 21 by the Z-bars riveted or spot-welded thereto effectively minimizes tendency to crush or collapse the door. In this latter construction, 75 it is also evident that the horizontal corrugations 20 merging at their ends with the vertical corrugations 21 also brace the latter and said horizontal corrugations may be so extended as to be riveted or spot-welded to 80 the adjacent flange of the Z-bar to still further increase the resistance against crushing or collapse.

At the upper edge of the door, the Z-bar D is applied as clearly shown in Fig. 2, 90 the upper panel A having a flat marginal portion as indicated at 27, to which the flange 28 of the Z-bar is riveted or otherwise secured. The other flange of the Z-bar is extended over the adjacent horizontal corrugation and riveted or spot-welded thereto similar to the application of the side 95 Z-bars F and G.

At the bottom edge of the door, the lower panel C is preferably provided not only with a flat marginal portion 29 in the general plane of the door, but with an inturned right angle flange 30, the latter forming a seal similar to the flange 25 on the rear edge of the door. The Z-bar E is applied in the 100 manner heretofore indicated for the Z-bars D, F and G and need not be specifically detailed. In connection with the lower Z-bar E, it will be noted that it provides a horizontal track as indicated at 31, thus adapting 105 it for cooperation with the roller 32 which is mounted on a fixed journal carried by a bracket 33, which in turn is secured to the side sill or other suitable portion of the car body. As will be understood, there will be 110 a series of such door supporting rollers 32 so as to at all times sustain the weight of the door in any position thereof. With the construction described, it is evident that the lower reinforcing Z-bar performs a plurality 115 of functions including that of providing a track for the door. The construction described is easy to fabricate and overcomes a difficulty heretofore experienced where sheet metal doors have been attempted and inability to provide a satisfactory supporting section for the doors has been encountered.

In the construction illustrated in Fig. 4, the door is made in the same manner as that illustrated in Figs. 1, 2 and 3 with the 120

addition of reinforcing bridging strips 34—34. These strips 34 extend lengthwise of the edge corrugations 21 and also of the uppermost and lowermost horizontal corrugations of the panels. Said strips are united to the flat marginal portions of the door by the same rivets 35 or other means employed for uniting the Z-bars with the flat marginal portions of the door. The

10 strips 31 bridge the respective edge corrugations and are united to the main portions of the sheet metal within the edge corrugations by rivets 36 or spot-welding so as to, in effect, produce a tube along 15 each edge of the door, the tubes thus formed providing great strength against indentation, crushing, distortion or warping. In addition, it is evident that the strips 34 which cover the vertical edge corrugations 20 21 will prevent any of the material or load in the car from lodging therein which minimizes the possibility of the load interfering with the opening of the door.

In the construction shown in Fig. 5, the 25 door is made substantially the same as that disclosed in Figs. 1, 2 and 3 except that vertical edge corrugation 21 are omitted, although the horizontal corrugations are retained. Z-bars E' are employed 30 along the respective edges united to the flat marginal portions 124 of the sheet metal as by the rivets 37 or spot-welding, the other flanges of the Z-bars E' being riveted or spot-welded inside of the flat marginal edges 35 124 as indicated at 38.

In the construction illustrated in Fig. 40 6, the main portion of the door formed by the sheet metal is the same as that illustrated in Figs. 1, 2 and 3, but instead of employing Z-bars around the edges, I employ angle irons 39, the same being riveted or spot-welded to the flat marginal portions 224 as indicated at 40.

The construction illustrated in Fig. 7, 45 is similar to that shown in Fig. 6 except that I employ a T-bar indicated at 41, the same being riveted or spot-welded to the flat marginal portions 324 of the sheet metal portions of the door as indicated at 42.

50 In Fig. 8, the construction is similar to that shown in Fig. 7 with the addition of a reinforcing bridging strip 434 that is secured to the flat marginal portions of the sheet metal portion of the door by the same rivets or other securing means 442 as is the T-bar 441. The strip 434 is secured to the sheet metal portions of the door within the edge corrugations by rivets or spot-welding as indicated at 436.

In Fig. 9, I employ a bridging strip 534 united within the edge corrugation 521 as by rivets or spot-welding indicated at 536, said strip 534 being extended beyond the sheet metal comprising the panels of the door and having secured thereto an angle

iron 43. The angle iron is applied with one flange thereof parallel to the strip 534 and the other flange extending at right angles thereto and away from the inner plane of the door. In this construction, the 70 sheet metal composing the panels of the main portion of the door will preferably be provided with an outturned flange indicated at 44 and riveted or spot-welded to the angle iron 43 as indicated at 45. 75

The construction illustrated in Fig. 10 corresponds to that shown in Fig. 6 and is a vertical section thereof showing the position of the upper and lower angle irons 39—39. 80

The construction illustrated in Fig. 11 is the same as that shown in Fig. 10 with the addition of a reinforcing or bridging strip 634 that is united to the sheet metal forming the panels or main portion of the door on each side of the respective upper and lower edge corrugations. 85

The construction shown in Fig. 12 is the same as that shown in Figs. 1, 2 and 3 with the addition of reinforcing or bridging strips 734 united to the main portions of the door by rivets or otherwise on opposite sides of the respective upper and lower horizontal corrugations. This construction differs also somewhat from that illustrated in Fig. 4 by having the upper panel of sheet metal inwardly flanged as indicated at 46. 95

In the construction illustrated in Fig. 13, the Z-bar E² is combined with a bridging strip 834 in a manner somewhat different 100 from that shown in Figs. 1, 2 and 3. In this construction, the upper and lower portions of the sheet metal forming the main portion of the door is formed with an outwardly inclined section 47 and a terminal flat edge 48 to which the outer flange of the Z-bar E² is riveted or spot-welded as indicated at 49. The bridging or reinforcing strip 834 is united to the sheet metal panels within the inclined portions 47 as 105 indicated at 50, the said bridging strips 834 being extended and riveted or otherwise rigidly united with the inner flanges of the Z-bars E² as indicated at 51. In this manner, it will be evident that I form a tube 110

in effect along the edges of the door by employing three elements, a part of the sheet metal panel, the bridging strip and the Z-bar. It will also be noted that the constructions shown in both of Figs. 12 and 13 are especially adapted for cooperation with supporting rollers at the bottoms of the doors, the track for said rollers being formed by the Z-bars as indicated in 115 said drawings where portions of the rollers are indicated more or less diagrammatically at 32—32.

The construction illustrated in Fig. 14 embodies a bridging or reinforcing strip 934, 120 an angle iron 52 and portions of the sheet 125

metal panels. The latter are formed with an outwardly inclined section 53, a short vertical section 54 parallel to the main plane of the door and an inturned marginal portion 55, the latter being riveted or otherwise secured to one flange of the angle iron 52 as indicated at 56. The bridging strip 934 is riveted or otherwise rigidly secured to the main portions of the panel sheets as indicated at 57, said strip 934 being riveted or otherwise rigidly secured as indicated at 58 along its outermost edge to the other flange of the angle iron 52. This construction also produces the effect of a tube along the edge 15 of the door by combining the three elements, the angle iron, the bridging strip, and a special formation of the panel sheets. In this construction as in those shown in Figs. 1, 2, 3, 12 and 13, the reinforcing commercial 20 rolled beam provides an efficient track for the door supporting rollers at the bottom thereof.

Although I have herein shown and described what I consider the preferred means 25 for carrying out my invention, the same are merely illustrative and various changes may be made without departing from the spirit of the invention, as, for instance, the sheet metal portions of the door may be 30 made in a single panel or in two panels and the reinforcement of the panels or sections of the door within the edges thereof may be done in other ways than those shown in the drawings, that is, by the use of horizontal 35 corrugations. I contemplate all changes and modifications that come within the scope of the claims appended hereto.

It will be noted that common characteristics of all of the forms illustrated in the 40 drawings are the flat multiply marginal edge portions of the doors and the formation of the sheet metal comprising the main part of the door in such way as to extend a portion of the sheet metal outwardly from 45 the main plane of the door so as to effectively strengthen the door against lateral or bending forces. The flat multiply marginal portions mentioned are sometimes of two thicknesses and sometimes of three thicknesses 50 but in each instance, one of the thicknesses is formed by a section of the reinforcing commercially rolled beam, whether it be an angle T or Z, and furthermore, the said rolled shapes are so formed and applied that 55 in every instance one section thereof is parallel to the said marginal portions of the doors and another section at right angles thereto. By this arrangement, the edges of the doors are very strongly braced against 60 indentation from forces applied in a direction parallel to the plane of the door and also against bending or prying outwardly. It is also evident that the reinforcing commercial shapes in conjunction with the other 65 strengthening indentations of the sheet

metal effectively strengthen the door against sagging or distortion in the plane of the door.

I claim:

1. A door of the character described, comprising sheet metal and commercially rolled shapes, the sheet metal having portions thereof extending outwardly from the inner plane of the door along the edges of the door, said shapes being secured to the sheet metal along the edges and each of said shapes including a section at right angles to the plane of the door also extending outwardly from said inner plane and a section parallel thereto, said shapes being rigidly united to said outwardly extending portions of the sheet metal, the door having multiply flat marginal portions, one ply of each of which is constituted by the section of the corresponding shape which extends parallel to said plane of the door.

2. A horizontally slideable door of the character described, comprised mainly of relatively thin sheet metal having indentations, including a bottom horizontally extending corrugation therein within the edges to strengthen the door against lateral thrusts, and a commercial shape secured along the bottom edge of the door and rigidly united to the sheet metal main portion of the door, said shape having one section thereof extending horizontally and perpendicular to the general plane of the door, the door being adapted for support at the bottom when moved horizontally.

3. A door of the character described, comprising a main portion formed of sheet metal, reinforcing bridging strips, and a reinforcing commercial shape along the bottom edge of the door, the sheet metal comprising the main portion of the door being corrugated and formed along its edges with portions thereof extending outwardly from the inner plane of the door, said bridging strips being united to the sheet metal forming the main portion of the door within the area defined by said outwardly extending portions thereof, said shape having a section thereof extended parallel to the plane of the door and rigidly united to the adjacent bridging strip to form a multiply lower edge, said shape having also a horizontal section extending perpendicular to the plane of the door, said shape being also rigidly united to the sheet metal forming the main part of the door, the lower edge of the door being of tube-like formation comprised of the lower strip, rolled shape and the sheet metal of the main body of the door, said rolled shape forming a horizontal lower edge for the door.

4. A door of the character described having the main portion thereof comprised of sheet metal, edge bridging strips rigidly united to the sheet metal forming the main

part of the door, and a Z-bar extending along the lower edge of the door, said Z-bar having one flange rigidly united to the lower part of the adjacent bridging strip to form a multiply edge, the other flange of the Z-bar being rigidly united to an outwardly extended portion of the sheet metal comprising the main part of the door.

5. A horizontally slidable door of the character described having the main portion thereof comprised of sheet metal, the sheet metal of the door, at the bottom thereof, having an outwardly offset portion; an additional reinforcing strip secured to the main sheet metal portion of the door at the bottom thereof above said offset portion; and a reinforcing commercial shape having two sections thereof at right angles to each other, one of said sections extending parallel to the main plane of the door and the other perpendicular to said plane, said reinforcing shape being secured to both said strip and said offset portion.

6. A door of the character described having the main portion thereof comprised of sheet metal, said sheet metal portion of the door having a corrugation adjacent and parallel to one edge thereof, said corrugation extending outwardly from the general plane of the door; and a reinforcing Z-bar rigidly secured to said edge of the door, said Z-bar having one flange thereof extending parallel to the main plane of the door and the web and the other flange thereof extended outwardly from said main plane of the door.

7. A door of the character described having the main portion thereof comprised of a plurality of sheet metal panels rigidly united, said panels being provided with transversely extending corrugations, and a plurality of Z-bars secured to the margins of the said main portion of the door comprised of the sheet metal panels, each of said Z-bars having one flange united to the sheet metal comprising the main portion and parallel thereto, the web of the Z-bar extending perpendicular to the general plane of the door and the other flange parallel thereto but offset therefrom.

8. A horizontally movable door of the character described having the main portion thereof comprised of sheet metal, said sheet metal, at the bottom of the door being provided with an outwardly offset portion; a horizontally extending bracing strip at the bottom of the door and rigidly united thereto; and a horizontally extending commercial shape at the bottom of the door rigidly united with said offset portion and the strip, said strip, offset portion and commercial shape forming an enclosed tube-like structure at the bottom of the door and a flat multiple-ply marginal section.

9. A door of the character described hav-

ing the main portion comprised of a plurality of sheet metal panels arranged one above the other and united along their adjoining edges, said panels being provided with outwardly extended transverse corrugations; and a plurality of commercial shapes rigidly united to said main portion of the door along the margins thereof, each of said shapes including two sections at right angles to each other, one section extending parallel to and substantially in the general main plane of the door, the other section extending perpendicularly to the main plane of the door.

10. A door of the character described, having the main body portion thereof composed of a plurality of sheet metal panels arranged one above the other and united along their adjoining edges, the lower of said panels being provided with a reinforcing corrugation, and a plurality of rigidifying members united to said main portion of the door along the margins thereof, the rigidifying member along the bottom margin of the door being of Z-cross-section and having a flange portion secured to the door substantially in the plane of the peak of said corrugation, and having its inner flange portion secured to the door substantially in the plane of the trough of said corrugation.

11. A door of the character described having a main body portion provided with a reinforcing corrugation; and a plurality of rigidifying members united to said main body portion of the door along the margins thereof, the rigidifying member along the bottom margin of the door being of Z-cross-section and having a flange portion secured to the door substantially in the plane of the peak of said corrugation, and having its inner flange portion secured to the door substantially in the plane of the trough of said corrugation.

12. A door of the character described having the main portion thereof comprised of a plurality of sheet metal panels arranged one above the other and united along their adjoining edges; and a plurality of commercial shapes rigidly united to said main portions of the door along the margins thereof each of said shapes including two sections at right angles to each other, one section extending parallel to and substantially in the general main plane of the door, the other section extending perpendicularly to the main plane of the door.

13. A door of the character described, having the main portion thereof comprised of a plurality of sheet metal panels arranged one above the other and united along their adjoining edges; and a reinforcing member secured to each of the front and rear edges of the door, each of said members having a flange lying against and rigidly secured to

the sheet metal of the main portion of the door and an integral section extending outwardly from the main plane of the door, said outwardly extended section being disposed inwardly from the corresponding margin of the door.

14. In a door of the character described, having the main portion thereof comprised of a plurality of sheet metal panels arranged

10 one above the other and united along their adjoining edges, each panel having a plurality of outwardly disposed corrugations therein extending parallel to the united edges of the panels; and rigidifying mem-

15 bers extending along and secured to the front and rear edges of said main portions of the door, each of said members having an outer flange lying against and rigidly secured to the sheet metal of the main portion

20 of the door, and an integral section extended outwardly from the main plane of the door and disposed inwardly of said respective flanges thereof.

15. A door comprising: a plurality of 25 sheet metal panels, each panel having corrugations formed therein and offset from the main plane of the sheets; means rigidly uniting the panels along adjacent edges; a stiffening flange along the adjacent edges of 30 the panels; and a stiffening flange section extending perpendicular to the plane of the sheets along the outer edges of the door, all 35 said stiffening flanges and corrugations extending from the main plane of the sheets to the same side.

16. In combination with a railway car 40 having a door opening, rollers arranged under said door opening, and a door comprising a sheet metal panel and a box-like rigidifying structure at its lower edge having a horizontal web bearing on said rollers, an upstanding flange to which the edge of the panel is secured, and a depending flange standing back of said rollers, said panel being formed with corrugations, which are pressed inwardly from the marginal portion of the panel.

17. In combination with a railway car 45 having a door opening, rollers arranged under said door opening, a door comprising a sheet metal panel and a rigidifying structure at its lower edge having a horizontal web bearing on said rollers, an upstanding flange to which the edge of the panel is secured, a depending flange standing back of 50 said rollers, said panel being formed with horizontally disposed corrugations which are pressed inwardly from the marginal portion of the panel, and a plate secured to 55 said depending flange and to one of said corrugations.

18. In combination with a railway car 60 having a door opening, door supporting means arranged under said door opening, and a sheet metal door provided at its lower

edge with a hollow box-like structure, the bottom of which bears on said door supporting means.

19. In combination with a railway car 70 having a door opening, rollers arranged under said door opening, and a door comprising a marginal frame, a sheet metal panel within said frame, and means at the lower edge of the door providing with said frame and panel a hollow box-like construction, the bottom of which bears on said rollers.

20. In combination with a railway car 80 having a door opening, rollers arranged under said door opening, and a door the upper portion of which consists of a single thickness of sheet metal and the lower portion of hollow box-like construction, the bottom of which bears on said rollers.

21. A metal side door for a railway car 85 adapted to slide on the outside of the car across the door opening comprising a sheet metal panel formed with rigidifying corrugations; a stiffening member angular in 90 cross section secured to the lower edge of the panel, and a flat plate secured to the projecting portion of the stiffening member and extending upwardly to one of the corrugations of the panel above the same so as to 95 constitute a hollow reinforcement for the lower edge of the door.

22. A metal side door for a railway car 100 adapted to slide on the outside of the car across the door opening comprising a sheet metal panel formed with horizontally disposed 105 rigidifying corrugations, a stiffening member angular in cross section secured to the lower edge of the panel, and a flat plate secured to the stiffening member and to the corrugated portion of the panel above 110 the same providing a box-like structure at the lower portion of the door.

23. A metal side door for a railway car 115 adapted to slide on the outside of the car across the door opening comprising a sheet metal panel formed with inwardly projecting 120 corrugations, a stiffening member at the lower edge of the panel and projecting inwardly therefrom, and a flat plate on the inside of the panel secured to the corrugated 125 portion of the panel and to said stiffening member.

24. A metal side door for a railway car 130 adapted to slide on the outside of the car across the door opening comprising a sheet metal panel formed with inwardly projecting, horizontal corrugations, a Z-bar at the lower edge of the panel and projecting inwardly therefrom, and a flat plate on the inside of the panel secured to one of said corrugations and to said Z-bar.

25. A metal side door for a railway car 135 adapted to slide on the outside of the car across the door opening comprising a sheet metal panel formed with a plurality of hori-

- zontally disposed, inwardly projecting corrugations which terminate within the edges of the panel to provide flat margins at the forward and rear edges of the door, angle bars secured to said forward and rear margins and having webs inwardly projecting therefrom, an angle bar secured to the upper edge of the panel having an inwardly projecting web, a Z-bar secured to the lower edge of the panel and projecting inwardly therefrom, and a flat plate on the inside of the panel at its lower edge secured to one of said corrugations and to said Z-bar.
26. A railway car door comprising a marginal frame consisting of members at the top, bottom and forward and rear edges which are angular in cross section with flanges lying in the front plane of the door and flanges projecting inwardly therefrom, and a sheet metal panel having its marginal edges secured flatwise to said first named flanges and formed with corrugations pressed inwardly from said marginal edges.
27. A railway car door comprising a marginal frame consisting of members at the top, bottom and forward and rear edges which are angular in cross section with flanges lying in the front plane of the door and flanges projecting inwardly therefrom, and a sheet metal panel having its marginal edges secured flatwise to said first named flanges and formed with corrugations pressed inwardly from said marginal edges to a depth corresponding substantially to the width of said marginal frame.
28. A railway car door comprising a marginal frame consisting of angle bars at the top, forward and rear edges having flanges in the front plane of the door and flanges projecting inwardly therefrom, and a Z-bar at the bottom, the intermediate web of which is horizontal and extends backwardly from the front plane of the door and a sheet metal panel having its marginal edges secured flatwise against the first named flanges of the angle bars, and the upwardly projecting flange of said Z-bar and formed with corrugations pressed inwardly from said marginal edges.
29. A railway car door comprising a marginal frame consisting of angle bars at the top, forward and rear edges having flanges in the front plane of the door and flanges projecting inwardly therefrom, and a Z-bar at the bottom, the intermediate web of which is horizontal and extends backwardly from the front plane of the door, a sheet metal panel having its marginal edges secured flatwise against the first named flanges of the angle bars and the upwardly projecting flange of said Z-bar and formed with corrugations pressed inwardly from said marginal edges, and a plate on the inside of said door secured to the depending flange of the Z-bar and to the sheet metal panel.
30. A railway car door comprising a marginal frame consisting of angle bars at the top, forward and rear edges having flanges in the front plane of the door, and flanges projecting inwardly therefrom, and a Z-bar at the bottom, the intermediate web of which is horizontal and extends backwardly from the front plane of the door, a sheet metal panel having its marginal edge secured flatwise against the first named flanges of the angle bars and the upwardly projecting flange of said Z-bar and formed with horizontal corrugations pressed inwardly from said marginal edges, and a plate on the inside of said door secured to the depending flange of the Z-bar and to one of said corrugations.
31. In combination with the door frame of a railway car, a track arranged above the door opening, guide brackets below said door opening, and a door comprising a marginal frame consisting of members at the top and forward and rear edges which are angular in cross section with flanges lying in the front plane of the door and flanges projecting inwardly therefrom, and a Z-bar bottom member, the intermediate web of which is horizontally arranged and extends backwardly from the front plane of the door, a sheet metal panel secured to the first named flanges of said top, forward and rear members and to the upstanding flange of said Z-bar and formed with inwardly extending, horizontal corrugations, and a plate on the inside of the door secured to the depending flange of said Z-bar, and to one of said corrugations, the lower edge of said plate and the depending flange of the Z-bar standing back of said guide flanges.
32. A railway car door comprising in combination a marginal rectangular frame, a sheet metal panel, and a plate cooperating with said frame and panel to provide a hollow box-like structure at the lower edge of the door.
33. A railway car door comprising, in combination a sheet metal panel formed with horizontally disposed corrugations, and a Z-bar at the lower edge of the panel having an upstanding flange to which the panel is secured, and an oppositely disposed depending flange, the intervening web of said Z-bar being substantially horizontal.
34. A railway car door the upper portion of which consists of a single thickness of sheet metal provided with angular members, for rigidifying its edges and formed with stiffening corrugations projecting into the space defined by said angular members and the lower portion of which consists of a hollow box-like construction lying approximately between the planes on opposite sides of said corrugations.
35. A railway car door comprising, in combination a marginal rectangular frame

consisting of members angular in cross section, and a sheet metal panel formed with corrugations terminating within the edges of the sheet and projecting into the space within said frame.

36. A railway car door comprising, in combination: a main portion consisting of a plurality of panels rigidly united, and a Z-bar at the lower edge of the bottom panel having an upstanding flange to which the panel is secured, and an oppositely disposed depending flange, the intervening web of said Z-bar being substantially horizontal.

37. A railway car door comprising, in combination: a main portion comprised of

a plurality of panels rigidly united, and Z-bars at the top and bottom edges of the top and bottom panels, respectively, each Z-bar having a flange extending inwardly toward the center of the door, and to which the respective panel edge is secured, and an oppositely disposed flange extended outwardly from the center of the door, the intervening web of each Z-bar being substantially horizontal.

In witness that I claim the foregoing I have hereunto subscribed my name this 1st day of May, 1919.

ALLAN S. BARROWS.
